United States Patent Office.

SAMUEL H. WALLIZE, OF WASHINGTONVILLE, PENNSYLVANIA.

Letters Patent No. 71,825, dated December 3, 1867.

IMPROVED BRAKE FOR SLEDS.

The Schedule referred to in these Letters Patent and making part of the same.

TO ALL WHOM IT MAY CONCERN:

Be it known that I, SAMUEL H. WALLIZE, of Washingtonville, Montour county, State of Pennsylvania, have invented an "Improved Brake for Sleds;" and I do hereby declare the following to be an exact description thereof, reference being had to the accompanying drawings, and to the letters of reference marked thereon, making a part of this specification, in which—

Figure 1 represents a side view of the sled and brake.

Figure 2, a rear view.

A represents the frame of the sled; B B, the runners; C, the front cross-bar, to which a tongue may be attached; D, the brake or drag-bar, with its forked ends E suspended to the cross-bar C at each side, and has a projection, G, at the lower side of the extremity of the drag-bar, which acts as a brake, to draw along on the snow or ice, and penetrate the snow or ice a sufficient depth to regulate the forward movement of the sled, or completely check and stop it, by means of the lever H, attached to the one end of a revolving roller, J, that operates on the rear end of the cross-frame, to which roller a double lever, K, is permanently fastened, projecting down and bearing upon the drag-bar D by means of a roller, L. Below the roller L a self-adjusting double lever, M, with a lower roller, N, clasps the drag-bar D, and allows the drag-bar to operate between the double lever M and the upper and lower rollers L and N, so that, by pressing upon the lever H, the double lever K, with its roller L, presses upon the drag-bar D, and presses the brake G into the snow or ice, and the movement of the sled is regulated or checked; and by raising the lever H, the drag-bar D is raised and held up against the frame of the sled.

What I claim as my invention, and desire to secure by Letters Patent, is—

The construction and arrangement of the levers H, K, and M, with their rollers L and N, when combined with the drag-bar D, and operating the brake G, as herein described; and for the purposes set forth.

SAM'L H. WALLIZE.
